Patented June 17, 1975

235,406

COMBINED FOOD STORAGE AND SERVING DISH

Robert Daenen, Erembodegem, Belgium, assignor to Dart
Industries Inc., Los Angeles, Calif.

Filed Jan. 9, 1974, Ser. No. 432,025

Term of patent 14 years

Int. Cl. D7—01

U.S. Cl. D7—76

FIG. 1

FIG. 2

FIG. 3.

FIG. 4.

FIG. 5.

FIG. 6.

FIG. 1.

FIG. 2.

FIG. 1 is a side elevational view of a combined food storage and serving dish showing my new design;

FIG. 2 is an end elevational view thereof;

FIG. 3 is a top plan view of the base member thereof;

FIG. 4 is a bottom plan view of the base member thereof;

FIG. 5 is an end elevational view of the base member thereof;

FIG. 6 is a top plan view of the cover member thereof;

FIG. 7 is a bottom plan view of the cover member thereof; and

FIG. 8 is an end elevational view of the cover member thereof.

I claim:

The ornamental design for a combined food storage and serving dish, substantially as shown.
